UNITED STATES PATENT OFFICE

TIMOTHY E. SHEA, OF RUTHERFORD, NEW JERSEY, ASSIGNOR TO WESTERN ELECTRIC COMPANY, INCORPORATED, OF NEW YORK, N. Y., A CORPORATION OF NEW YORK

WAVE FILTER

Application filed February 27, 1926. Serial No. 91,219.

This invention relates to wave filters, and has for its objects the reduction of the cost of filter structures, and the more efficient use of the material used in the construction of the electrical elements.

The features of the invention may be most readily described by comparing the new and improved structures embodying the invention with the well known ladder, or series-shunt, type of filter described in U. S. patent to G. A. Campbell No. 1,227,113 issued May 22, 1917. In filters of that type there is frequently found a star combination of three capacities or a delta combination of three inductances, each element in the combination having a different impedance coefficient from the others.

In accordance with the present invention these combinations are replaced respectively by delta combinations of smaller capacities and star combinations of small inductances, thereby producing networks which are novel as to structural form; which possess the same electrical characteristics as the corresponding ladder type structure; and which are more economical in the use of material.

The nature of the invention will be more fully understood by referring to the following detailed description and to the accompanying drawings, forming a part thereof, of which, Figs. 1 and 2 illustrate a general theorem on which the invention is based; Figs. 3, 4 and 5 illustrate the steps in the development of the network of Fig. 5 in which the invention is embodied; and Figs. 6, 7 and 8 show in a corresponding manner the development of an alternative species of the invention.

Referring to Figs. 1 and 2, it has been shown by A. E. Kennelly in an article entitled "The equivalence of triangles and three-pointed stars in conducting networks" published in the Electrical World and Engineer, New York, Vol. XXXIV, No. 12, September 16, 1899, that a star network of three general

impedances Z_a , Z_b and Z_c , may be equivalent to a delta network of impedances Z'_a , Z'_b and Z'_c , with respect to all electrical properties ascertainable from measurements made at any of the corresponding terminals. The conditions under which the equivalence is obtained are expressed by the following equations:

$$Z_a = \frac{Z'_a Z'_c}{Z'_a + Z'_b + Z'_c}; \quad Z'_a = Z_b + Z_c + \frac{Z_b Z_c}{Z_a}; \quad 55$$

$$Z_b = \frac{Z'_a Z'_a}{Z'_a + Z'_b + Z'_c}; \quad Z'_b = Z_c + Z_a + \frac{Z_c Z_a}{Z_b}; \quad (1)$$

$$Z_c = \frac{Z'_a Z'_b}{Z'_a + Z'_b + Z'_c}; \quad Z'_c = Z_a + Z_b + \frac{Z_a Z_b}{Z_c}; \quad 60$$

It is always possible to construct a network of the one type which will be equivalent to a given network of the other type at at least one selected frequency, regardless of the nature of the impedance in the given network.

Equivalence at all frequencies, however, is obtained only when the impedances of the given network are all of the same type and are related to each other in magnitude by simple numerical factors.

A delta network of capacities, for example, can be constructed, which is at all frequencies equivalent to a given star network of capacities, and so also with regard to networks of inductances, or of complex impedances having the same resonance frequencies.

An examination of the equations shows that the total impedance of the three branches of the delta network is greater than twice the sum of the impedances of the branches of the corresponding star network. It follows then, that the total capacity in a delta network of condensers will be less than half the total capacity in the corresponding star network, and that the total inductance in a star network of inductance coils will be less than half the total inductance in the corresponding delta network.

It is therefore advantageous in any trans-

mission network to use delta networks of capacities rather than star networks wherever possible, and similarly to use inductances in star connection rather than in delta.

The application of the star delta transformation, in connection with wave filters, is illustrated by the two examples shown in Figs. 3 to 7. Fig. 3 shows the elementary structure of a composite high-pass wave filter comprising one symmetrical T section and two half sections.

The symmetrical section includes two series capacities C_{12} and a shunt resonant circuit $L_{22} C_{22}$; the half sections are of similar structure, but employ impedance elements of different values. The sections are assumed to be all alike in the respect, that at the junction points each section has the same characteristic, or image, impedance as the section to which it is joined, and they are further assumed to have unequal propagation constants.

Formulae relating to the design of composite wave filters may be found in an article by O. J. Zobel, "Theory and design of uniform and composite electric wave filters", published in the Bell System Technical Journal, Vol II, January, 1923; and the general procedure in design is described by K. S. Johnson and T. E. Shea in the same journal, Vol. IV, No. 1, January, 1925, in a paper entitled "Mutual inductance in wave filters with an introduction on filter design".

It has been found that the most practicable method, and probably the only practicable method, of designing composite filters, is based upon a consideration of the properties of simple symmetrical sections of T or of II form. The T sections are sometimes known as "series-terminated", or "mid-series" sections, and the II sections as "shunt-terminated", or "mid-shunt" sections.

In accordance with the principles disclosed in the above noted articles it is possible to choose a variety of sections having different attenuation characteristics and to fit them together so that the attenuation of each is contributed to the whole, without the introduction of reflection losses at the junction points. In this way the attenuation of a filter may be built up to meet any requirement of selectivity.

In the specific example shown in Fig. 1 the attenuation is characterized by three points of infinite attenuation corresponding respectively to the resonance frequencies of the three shunt circuits. The infinite attenuation points, of course, occur in the region of attenuation below the range of free transmission.

Ordinarily the design is completed by merging like elements of contiguous branches of the component sections into single elements. In the specific instance of Fig. 3 this step results in the structure of Fig. 4 in which

the series capacities C_a and C_b are respectively equal to the resultant capacities of the series combinations C_{11} , C_{12} and C_{12} , C_{13} . The star connected system C_a , C_b and C_{22} , in general is made up of unequal capacities, that is, it lacks symmetry of any sort whatever, this being a consequence of the arbitrary manner in which the sections are selected.

In accordance with the invention the design is carried a step farther, and the star connected network of capacities is replaced by a delta connected network of smaller capacities, the values of which are computed by means of equations 1. The final form of the filter network is shown in Fig. 5. The values of the capacities, C'_a , C'_b and C'_c , which constitute the delta network are respectively:

$$C'_a = \frac{C_b C_{22}}{C_a + C_b + C_{22}}, \quad 85$$

$$C'_b = \frac{C_a C_{22}}{C_a + C_b + C_{22}}, \quad (2)$$

and

$$C'_c = \frac{C_a C_b}{C_a + C_b + C_{22}}. \quad 90$$

The transmission properties of the network of Fig. 5 may be determined by analytical methods when the coefficients of the impedance elements are given, but the reverse process of determining the coefficients of the elements when the transmission properties is specified, is extremely difficult, unless the procedure already outlined is followed. According to this procedure the network is related to an equivalent network having several sections of the simple series shunt type.

The development of a related type of network, in which the star-delta transformation of inductance networks is involved, is shown in Figs. 6, 7 and 8.

The elementary composition of the network is shown, in Fig. 6, to include a symmetrical II type section, and two half sections of similar form; all of the elementary sections involving unlike impedance coefficients. The network is, like that of Fig. 5, a high-pass wave filter. It is analogous to that of Fig. 3, in that each section contributes a frequency for which the attenuation is infinite. In this case however, the infinite attenuation is produced by anti-resonant circuits in series with the line instead of by resonant circuits in shunt.

Design formulae for the coefficients of the elements in the elementary sections are given in the references hereinbefore mentioned.

Fig. 7 shows the filter design as it would ordinarily be completed by simply merging contiguous elements of like type into single units. Inductance L'_b corresponds to the parallel connection of L_{24} and L_{25} in Fig. 6; inductance L'_{12} to L_{25} and L_{26} ; and inductance L'_{13} to inductance L_{15} in Fig. 6.

Fig. 8 shows the network completed in ac-

cordance with the invention, a star network of inductances, L_a , L_b and L_c , being substituted for the delta network constituted by inductances, L'_a , L'_b , and L'_c of Fig. 7. The values of the star inductances are as follows:

$$L_a = \frac{L'_b L'_c}{L'_a + L'_b + L'_c},$$

$$L_b = \frac{L'_c L'_a}{L'_a + L'_b + L'_c},$$

and

$$L_c = \frac{L'_a L'_b}{L'_a + L'_b + L'_c}.$$

Two specific networks embodying the invention have been described, each of which possesses a certain unity of structure which, in addition to the feature of economical use of materials, distinguishes it from the series-shunt network electrically equivalent thereto.

It is to be understood, however, that the invention is not limited in its scope to the specific embodiments in connection with which it has been described, but only in accordance with the appended claim.

What is claimed is:

A wave filter network having a pair of input terminals, a pair of output terminals, and two line paths therebetween, said network including three inductive impedance paths arranged in shunt relation to said line paths, a delta connected group of three capacities included in one line path each terminal of said group being connected respectively to one of said shunt impedances, and said network being electrically equivalent to a prototype wave filter network comprising three filter sections of series-shunt type which are dissimilar to each other in their structure and transmission characteristics.

In witness whereof, I hereunto subscribe my name this 26th day of February, A. D. 1926.

TIMOTHY E. SHEA.
